UNITED STATES PATENT OFFICE.

WILLIAM H. KENT, OF BROOKLYN, NEW YORK.

FAN DEVICE.

Application filed February 12, 1923. Serial No. 618,604.

To all whom it may concern:

Be it known that I, WILLIAM H. KENT, a citizen of the United States, and residing at Brooklyn, in the county of Kings and State 5 of New York, have invented certain new and useful Improvements in Fan Devices, of which the following is a specification, such as will enable those skilled in the art to which it appertains to make and use the 10 same.

This invention relates to fan devices and particularly to devices of this class designed to be supported in connection with the back of a rocking chair and to be suspended over 15 the head of an occupant of such chair, and the object of the invention is to provide a fan device of the class and for the purpose specified which may be detachably mounted in connection with the back of a rocking 20 chair and provided with means for securing said device in connection with said chair, a further object being to provide means for adjustably supporting a fan element in connection with said device to regulate the relative 25 position thereof with reference to the occupant of the chair, a further object being to provide a flexible and adjustable backing member for the fan device which may serve as a head rest, and with these and other objects in view, the invention consists in a device of the class and for the purpose specified, which is simple in construction, efficient in use and which is constructed as 30 hereinafter described and claimed.

The invention is fully disclosed in the following specification, of which the accompanying drawing forms a part, in which the separate parts of my improvement are designated by suitable reference characters in 35 each of the views, and in which:—

Fig. 1 is a perspective view showing my improved fan device mounted in connection with the back member of a rocking chair, only part of said chair being shown.

Fig. 2 is a partial section on the line 2—2 of Fig. 1 on an enlarged scale; and,

Fig. 3 is a partial section on the line 3—3 of Fig. 2.

In Fig. 1 of the drawing, I have indicated at 5, the top portion of the back of a rocking chair and at 6 I have shown one of my improved fan devices mounted in connection therewith. The fan device 6 comprises in the construction shown a rod 7 on 55 which is mounted a sleeve 8 which is of slightly less longitudinal dimensions than

the rod 7 and mounted on said rod are two frame members 9 and 10, which are held in place by wing nuts or the like 11 in threaded engagement with the rod 7.

The frame member 9 is substantially yoke-shaped in form and comprises side arms 12, the free ends of which are provided with eyes 13 adapted to be passed over the rod 7, and the crosshead portion of the frame 9 has a forwardly directed and reduced extension 14 on which is pivotally suspended a fan element 15 as clearly shown in Figs. 1 and 2 of the drawing.

The frame member 10 is composed of two independent side members 16 each of which consists of substantially parallel rods 17 joined at one end by a loop 18, which is passed over the rod 7, and the free ends of the rods 17 are enlarged as shown at 19 and 20 preferably provided with felt facings 20 on their inner or adjacent faces. Rings 21 are mounted on the rods 17 and adjustable longitudinally thereof to clamp the free or head ends 19 of said rods onto the top of the back 25 member 5 of a rocking chair, as clearly illustrated in Fig. 1 of the drawing, it being understood that the rod 17 of the frame member 10 or the separate members 16 thereof form jaws for gripping the back of a 30 rocking chair with my improved fan device in connection therewith.

I also preferably mount upon the sleeve 8 a supplemental sleeve 22 on which is wound a fabric curtain 23, the sleeves 22 being free to rotate on the sleeve 8 and the end of the curtain 23 is provided with a rod 24 slidably mounted on one of the rods 17 of each of the members 16. It will be understood that by lowering the fabric curtain 23 the same may be used, if desired, as a support for the head of the occupant of the rocking chair, or in other words, used as a head rest and especially if the back member 5 of the rocking chair is considerably lower 35 than the head of the occupant of the chair. The curtain 23 may also be used as a sun or light shade if desired.

It will be understood that in the use of my improved device and after the same has been mounted in connection with the back member of a rocking chair, the operation of actuating said chair will automatically transmit a forward and backward reciprocating movement to the fan element 15 to automatically fan the occupant of the chair. It will be understood that the frame 9 may

be adjusted on the rod 7 to raise and lower the relative position of the fan element 15 by simply loosening the wing nuts 11, and while I have shown certain details of construction for carrying my invention into effect, it will be understood that I am not necessarily limited to these details, and various changes therein and modifications thereof may be made within the scope of the appended claims without departing from the spirit of my invention or sacrificing its advantages.

Having fully described my invention, what I claim as new and desire to secure by Letters Patent, is:—

1. A fan device of the class described comprising a rod, a sleeve mounted on said rod and of less longitudinal dimensions than said rod, a substantially U-shaped frame member the side members of which are mounted on said rod outwardly of said sleeve, a fan element movably mounted in connection with said frame, and two pairs of parallel rods mounted in connection with the ends of said first named rod and the free ends of which are provided with enlarged heads.

2. A fan device of the class described comprising a rod, a sleeve mounted on said

rod and of less longitudinal dimensions than 30 said rod, a substantially U-shaped frame member the side members of which are mounted on said rod outwardly of said sleeve, a fan element movably mounted in connection with said frame, and two pairs of parallel rods mounted in connection with the ends of said first named rod and the free 35 ends of which are provided with enlarged heads having fibrous facings.

3. A fan device of the class described comprising a rod, a sleeve mounted on said rod and of less longitudinal dimensions than said rod, a substantially U-shaped frame member the side members of which are mounted on said rod outwardly of said 40 sleeve, a fan element movably mounted in connection with said frame, two pairs of parallel rods mounted in connection with the ends of said first named rod and the free 45 ends of which are provided with enlarged heads having fibrous facings, and means mounted on the separate pairs of rods for clamping a suitable support therebetween.

In testimony that I claim the foregoing 55 as my invention I have signed my name this 9th day of Feb. 1923.

WILLIAM H. KENT.
